[57] CLAIM

The ornamental design for a combined rod and reel, as shown.

DESCRIPTION

FIG. 1 is a perspective view of the combined rod and reel showing my new design;

FIG. 2 is a top plan view thereof;

FIG. 3 is a side elevational view thereof;

FIG. 4 is a bottom view thereof;

FIG. 5 is a side elevational view thereof opposite to that shown in FIG. 3;

FIG. 6 is a front elevational view thereof; and

FIG. 7 is a rear elevational view thereof.
